ALKOXYALKYL ESTERS OF IODO-ALKOXY SUBSTITUTED PHENYL ACETIC ACIDS

Sydney Archer, Albany, N. Y., assignor to Sterling Drug Inc., New York, N. Y., a corporation of Delaware

No Drawing. Application January 29, 1949,
Serial No. 73,663

12 Claims. (Cl. 260—473)

1

This invention relates to alkoxyalkyl esters of iodo-lower-alkoxyphenylacetic acids and to their preparation.

My new compounds are opaque to X-rays and are therefore valuable as contrast media in the roentgenological examination of body cavities, for which purpose they can be administered directly into the cavity to be outlined.

I have found that these substances are of particular value in the roentgenological examination of the spinal chord and sub-arachnoid space, i. e., in that branch of radiography known as myelography. An ideal myelographic agent is one which is easily and rapidly administered and may be distributed readily and evenly to various parts of the cerebrospinal system, without, however, diffusing so rapidly that the radiopacity is lost. It should be eliminated readily, preferably without mechanical means, and be of low toxicity and tolerated in other ways by the patient.

Up to the present time, the various agents used for myelography include gases, such as air and oxygen, thorium dioxide sols, iodized oils and, more recently, a product consisting of a mixture of ethyl esters of isomeric iodophenylundecyclic acids. Each of these agents has certain disadvantages. Gases, although good contrast media, are difficult to administer properly, since their use requires removal of part of the cerebrospinal fluid, a procedure which can result in dangerous complications. Thorium dioxide sols lack the objectionable qualities of gases but have been found to cause untoward reactions, as well as imposing the possibility of eventual injury from residual radioactivity. Iodized and brominized oils, such as iodized poppyseed oil, iodized sesame oil, iodized rapeseed oil, and brominized olive oil, are effective contrast agents and non-toxic, but are largely unsatisfactory because of their high viscosity, and slightly irritating properties. They must be injected under pressure and after examination be withdrawn by aspiration, for otherwise they remain largely unabsorbed for a period of years and may result in cicatrix formation due to prolonged contact with the tissues. Their high viscosity tends to cause separation of the oil into globules, rendering diagnosis difficult. The mixture of ethyl iodophenylundecylates is undoubtedly the best myelographic agent thus far produced. It is less viscous than the iodized glyceride oils and, therefore, is more easily introduced, withdrawn and absorbed. However, it is reported that at least a year is required for complete absorption and elimination of as little as 0.5 to 1.0 cc. in man.

Although the possibility of using water-soluble

2

radiopaque media as myelographic agents has been investigated, these compounds have been found unsatisfactory for a number of reasons. Diffusion is too rapid, and the compound becomes diluted with the spinal fluid, thereby losing its radiopacity unless a large quantity is injected, whereupon toxicity becomes a major factor, as the substance is then rapidly absorbed into the circulatory system.

10 The alkoxyalkyl esters of iodo-lower-alkoxyphenylacetic acids have many advantages over the above-described myelographic agents. They are much more readily eliminated from the organism without mechanical means, being completely absorbed from the spinal canal in a matter of days as compared to months or years with media now in general use. The esters of my invention have the further advantage of being pure compounds instead of a mixture of isomers, and 15 have in general a greater radiopacity than the old iodized oils, due to a higher percentage of iodine, particularly among lower members of the series. The new compounds also cause little or no irritation of animal membranes and are relatively non-toxic.

20 My compounds have the general formula

wherein R and R' are lower alkyl groups and Y is a lower alkylene radical. By a lower alkyl group I mean one having preferably six carbon atoms or less. The total carbon content of my compounds ranges from 12 to about 16 carbon atoms.

40 They are synthesized by esterification of an iodoalkoxyphenylacetic acid with an alkoxyalkanol either by direct interaction of the two substances or by closely related reactions which are described below. The intermediate iodoalkoxyphenylacetic acids may be prepared by various methods commonly used for introduction of iodine into an aromatic ring. If a compound is desired 45 where the iodine is in the ortho or para position with respect to the alkoxy group, direct iodination of an alkoxyphenylacetic acid may be employed. If the iodine is not to be ortho or para to the alkoxy group, indirect methods must be used such as replacement of an amino group by iodine (Sandmeyer reaction) in an aminoalkoxyphenylacetic acid.

50 The alkoxyiodophenylacetic acid may be esterified by one of the following methods: (1), the acid and an alkoxyalkanol are combined di-

rectly optionally in the presence of an acid catalyst; (2), said acid in the form of a reactive derivative, such as the acid halide or anhydride, is reacted with an alkoxyalkanol; or (3), a metallic salt of said acid is reacted with an alkoxyalkyl halide.

Examples of intermediate acids which may be used in my invention include 3-iodo-4-methoxyphenylacetic acid, 2-iodo-5-methoxyphenylacetic acid, 3-iodo-6-methoxyphenylacetic acid, 3-iodo-5-methoxyphenylacetic acid, 3-iodo-4-ethoxyphenylacetic acid, 3-iodo-4-propoxyphenylacetic acid, 2-iodo-5-ethoxyphenylacetic acid, 2-iodo-5-propoxyphenylacetic acid, etc.

Examples of the intermediate alcohols which may be used include 2-methoxyethanol, 2-ethoxyethanol, 2-n-propoxyethanol, 2-isopropoxyethanol, 2-n-butoxyethanol, 3-methoxypropanol, 3-ethoxypropanol, 3-n-propoxypropanol, 3-isopropoxypropanol, 3-n-butoxypropanol, 4-methoxybutanol, 4-ethoxybutanol, etc.

The above-named alcohols when esterified by the methods described using some of the acids named above give compounds within the scope of my invention including such species as 2-methoxyethyl 3-iodo-4-methoxyphenylacetate, 2-methoxyethyl 2-iodo-5-methoxyphenylacetate, 2-propoxyethyl 3-iodo-6-methoxyphenylacetate, 2-isopropoxyethyl 3-iodo-5-methoxyphenylacetate, 2-butoxyethyl 3-iodo-4-methoxyphenylacetate, 3-methoxypropyl 3-iodo-4-methoxyphenylacetate, 3-ethoxypropyl 3-iodo-4-methoxyphenylacetate, 3-isopropoxypropyl 3-iodo-4-methoxyphenylacetate, 3-butoxypropyl 3-iodo-4-methoxyphenylacetate, 4-methoxybutyl 3-iodo-4-methoxyphenylacetate, 2-ethoxyethyl 3-iodo-4-propoxyphenylacetate, 2-ethoxyethyl 2-iodo-5-ethoxyphenylacetate and 2-ethoxyethyl 2-iodo-5-propoxyphenylacetate.

The following examples will illustrate my invention more fully but should not represent a limitation in the scope thereof.

EXAMPLE 1

(a) 3-iodo-4-methoxyphenylacetic acid

A solution of 30 g. of p-methoxy-phenylacetic acid in 140 ml. of 50% acetic acid was heated to 80° C., and a solution of 12 ml. of iodine monochloride in 12 ml. of acetic acid was added dropwise. Heating was continued at 80° C. for one hour, and the mixture was poured into about 500 ml. of water. Sulfur dioxide was bubbled through the suspension to decolorize it, and the solid product was collected by filtration. The product was then dissolved in hot alcohol, water was added and the solution was again decolorized with sulfur dioxide. Upon cooling, the product crystallized giving 42 g. (79%) of 3-iodo-4-methoxyphenylacetic acid, M. P. 122-124° C. When recrystallized from dilute alcohol it melted at 123-124° C.

Anal.—Calcd. for $C_9H_7IO_3$: I, 43.45. Found: I, 43.30.

(b) 2-ethoxyethyl 3-iodo-4-methoxyphenylacetate

A mixture of 22 g. of 3-iodo-4-methoxyphenylacetic acid and 50 ml. of thionyl chloride was heated gently at reflux temperature for 90 minutes. The excess thionyl chloride was then removed in vacuo, and 50 ml. of beta-ethoxyethanol

was added to the residue. After warming for 3 hours the mixture was poured into ice water and thoroughly extracted with ether. The ether extracts were then washed with dilute sodium carbonate solution, then with water and dried. After removal of the ether the residual oil was distilled. The fraction boiling at 173-175° C. (0.6 mm.) was redistilled to give 11 g. of 2-ethoxyethyl 3-iodo-4-methoxyphenylacetate, B. P. 172-175° C. (0.5 mm.); $n_D^{25}=1.5572$; viscosity (25°C.) = 50.3 cs.

Anal.—Calcd. for $C_{13}H_{17}IO_4$: C, 42.88; H, 4.71; I, 34.86. Found: C, 42.80; H, 4.98; I, 35.47.

EXAMPLE 2

2-methoxyethyl 3-iodo-4-methoxyphenylacetate

15 A mixture of 30 g. of 3-iodo-4-methoxyphenylacetic acid and 150 ml. of beta-methoxyethanol was refluxed for about 15 hours. The mixture was then poured into ice-water and thoroughly extracted with ether. The ether extracts were washed with dilute sodium carbonate solution, then with water and dried. After removal of the ether the residual oil was fractionated at reduced pressure to give 9.8 g. of 2-methoxyethyl 3-iodo-4-methoxyphenylacetate, B. P. 167-169° C. (0.6 mm.); viscosity (25°C.) = 56.2 cs.

Anal.—Calcd. for $C_{12}H_{16}IO_4$: C, 41.04; H, 4.27; I, 36.14. Found: C, 41.32; H, 4.35; I, 36.50.

EXAMPLE 3

(a) 2-iodo-5-methoxyphenylacetic acid

A solution of 230 g. of m-methoxyphenylacetic acid in 720 ml. of acetic acid and 720 ml. of water was heated to 80° C. Then a solution of 324 g. of iodine monochloride in 110 ml. of acetic acid was added dropwise over a period of one-half hour. The mixture was kept at this temperature for two hours and then allowed to stand at room temperature for two days. It was then warmed to redissolve the solid which had separated and was treated with sulfur dioxide in order to decolorize the solution. The resulting solution was cooled, and the solid which separated was collected by filtration. A recrystallization of this solid from ethyl alcohol gave a first crop of 178 g., M. P. 123-124° C. and a second crop of 75 g., M. P. 119-123° C. The two crops were combined and recrystallized from a benzene-petroleum ether mixture, giving 220 g. of 2-iodo-5-methoxyphenylacetic acid, M. P. 127-130° C. An analytical sample was obtained by further recrystallization from ethyl alcohol and melted at 129-130° C.

Anal.—Calcd. for $C_9H_7IO_3$: I, 43.45. Found: I, 43.50.

(b) 2-methoxyethyl 2-iodo-5-methoxyphenylacetate

70 A mixture of 30 g. of 2-iodo-5-methoxyphenylacetic acid, 150 ml. of 2-methoxyethanol and 2 ml. of concentrated sulfuric acid was refluxed for about fifteen hours. The mixture was then poured into ice water and thoroughly extracted with ether. The ether extracts were washed with dilute sodium carbonate solution, then with water and dried. After removal of the ether the residual oil was fractionated at reduced pressure giv-

ing 16.7 g. of 2-methoxyethyl 2-iodo-5-methoxyphenylacetate, B. P. 166-168° C. (0.6 mm.); $n_D^{25}=1.5636$; viscosity (25° C.) = 45.9 cs.

Anal.—Calcd. for $C_{12}H_{15}IO_4$: C, 41.16; H, 4.31; I, 36.24. Found: C, 41.40; H, 4.56; I, 36.45.

EXAMPLE 4

2-ethoxyethyl 2-iodo-5-methoxyphenylacetate

A mixture of 30 g. of 2-iodo-5-methoxyphenylacetic acid, 150 ml. of 2-ethoxyethanol and 2 ml. of concentrated sulfuric acid was refluxed for about fifteen hours. The mixture was then poured into ice water and thoroughly extracted with ether. The ether extracts were washed with dilute sodium carbonate solution, then with water and dried. After removal of the ether the residual oil was fractionated at reduced pressure. The fraction boiling at 161-195° C. (0.5 mm.) was redistilled giving 16.7 g. of 2-ethoxyethyl 2-iodo-5-methoxyphenylacetate, B. P. 166-168° C. (0.6 mm.); $n_D^{25}=1.5636$; viscosity (25° C.) = 45.9 cs.

Anal.—Calcd. for $C_{12}H_{15}IO_4$: C, 41.16; H, 4.31; I, 36.24. Found: C, 41.40; H, 4.56; I, 36.45.

I claim:

1. Beta-ethoxyethyl 3-iodo-4-methoxyphenylacetate having the formula

2. Beta-ethoxyethyl 2-iodo-5-methoxyphenylacetate having the formula

3. Beta-methoxyethyl 2-iodo-5-methoxyphenylacetate having the formula

4. A compound of the formula

containing a total of from 12-16 carbon atoms, wherein R and R' are lower-alkyl groups and Y is a lower-alkylene radical in which at least 2 carbon atoms separate the carboxyl group from the OR' group.

5. A compound of the formula

containing a total of from 12-16 carbon atoms, wherein R and R' are lower-alkyl groups and Y is a lower-alkylene radical in which at least 2 carbon atoms separate the carboxyl group from the OR' group.

6. A compound of the formula

containing a total of from 12-16 carbon atoms, wherein R and R' are lower-alkyl groups and Y is a lower-alkylene radical in which at least 2 carbon atoms separate the carboxyl group from the OR' group.

7. A compound of the formula

containing a total of from 12-16 carbon atoms, wherein R' is a lower-alkyl group and Y is a lower-alkylene radical in which at least 2 carbon atoms separate the carboxyl group from the OR' group.

8. A compound of the formula

containing a total of from 12-16 carbon atoms, wherein R' is a lower-alkyl group and Y is a lower-alkylene group in which at least 2 carbon atoms separate the carboxyl group from the OR' group.

9. A process of preparing a compound of the formula

containing a total of from 12-16 carbon atoms, wherein R and R' are lower-alkyl groups and Y is a lower-alkylene radical in which at least 2 carbon atoms separate the carboxyl group from the OR' group, which comprises reacting a member of the group consisting of an acid of the formula

the acid halide of said acid and the acid anhydride of said acid with a lower-alkoxyalkanol.

10. A process of preparing a compound of the formula

containing a total of from 12-16 carbon atoms, wherein R and R' are lower-alkyl groups and Y is a lower-alkylene radical in which at least 2 carbon atoms separate the carboxyl group from the OR' group, which comprises reacting the acid halide of an acid of the formula

with a lower-alkoxyalkanol.

11. A process of preparing a compound of the formula

containing a total of from 12-16 carbon atoms, wherein R and R' are lower-alkyl groups and

Y is a lower-alkylene radical in which at least 2 carbon atoms separate the carboxyl group from the OR' group, which comprises reacting an acid of the formula

with a lower-alkoxyalkanol in the presence of a mineral acid catalyst.

12. A process of preparing a compound of the formula

containing a total of from 12-16 carbon atoms, wherein R and R' are lower-alkyl groups and Y is a lower-alkylene radical in which at least 2 carbon atoms separate the carboxyl group from the OR' group, which comprises reacting a metallic salt of an acid of the formula

5 with a lower-alkoxyalkyl halide.
